UNITED STATES PATENT OFFICE.

HARRY GLAENZER AND LAWRENCE W. HANCE, OF PHILADELPHIA, PENNSYLVANIA.

CYLINDER SADDLE.

Application filed May 26, 1927. Serial No. 194,371.

The object of our invention is to make a cylinder saddle containing three cylinders and their valve-chests in a single cast metal structure.

5 The drawings illustrate a construction in which the three cylinders are high pressure cylinders, but it will be understood that the invention can be applied to a three-cylinder structure in which two of the cylinders are 10 low pressure cylinders and the other cylinder a high pressure cylinder.

In the accompanying drawings:

Fig. 1 is an end view of a locomotive cylinder saddle, the heads of the cylinders and 15 valve-chests being removed to avoid confusion.

Fig. 2 is a plan view;

Fig. 3 is an inverted plan view;

Fig. 4 is a transverse section on the line

20 A—A, Fig. 2;

Fig. 5 is a sectional plan view on the line

B—B, Fig. 1;

Fig. 6 is a sectional elevation on the line

C—C, Fig. 1;

25 Fig. 7 is a sectional elevation on the line

D—D, Fig. 1;

Fig. 8 is a sectional elevation on the line

E—E, Fig. 1;

Fig. 9 is a transverse sectional view on

30 the line F—F, Fig. 5;

Fig. 10 is a transverse sectional view on the line G—G, Fig. 5; and

Fig. 11 is a transverse sectional view on the line H—H, Fig. 6.

35 The cylinder saddle 1 is made in a single casting and has flanges 2—2 which are rigidly secured to the longitudinal frames 3—3 of the locomotive shown by dotted lines in Figs. 1 and 4.

40 The cylinder saddle has three cylinders 4, 4^a and 5. The cylinders 4—4^a are on either side of the structure and overhang the locomotive frames 3—3 as shown in Fig. 1.

45 The cylinder 5 is centrally located, and in the present instance is inclined as shown in Fig. 8, while the side cylinders 4—4^a are horizontal. This arrangement of the cylinders allows the connecting rod of the central cylinder to clear the mechanism and to be coupled directly with the centrally lo-

cated crank on one of the driving axles of the locomotive.

6—6^a are the inlet passages for steam connecting directly with the steam-chests 7—7^a of the two cylinders 4—4^a, respectively. 55 The inlet passage 6 also communicates with the steam-chest 8 of the centrally located cylinder 5 through a passage 9 as shown in Fig. 4. The steam-chests 7—7^a communicate at each end with the cylinders 4—4^a, 60 respectively, through passages 10—10^a, Figs. 5, 6 and 11, and with the main exhaust passage 12 through passages 13—13^a.

The main exhaust passage 12 extends partly around the central cylinder 5, and its 65 outer end communicates with the nozzle in the smoke-box of the locomotive (not shown). The end of the exhaust passage extends above the curved saddles 15 of the cylinder structures and is well within the 70 smoke-box of the locomotive.

The steam-chest 8 of the central cylinder communicates with said cylinder through passages 16, Figs. 5 and 9, and with the main exhaust passage 12 through a passage 75 17, Fig. 7.

In the cylinders are the usual bushings 18 and in the steam chests are the usual two-part perforated bushings 19.

By the above construction, the three 80 cylinders and their steam chests are formed in a comparatively simple casting, in which the passages are short and direct and the main exhaust passage extends under the central cylinder and around one side thereof to the 85 nozzle opening at the upper portion of the casting.

The steam inlet passages are directly above the steam chests of the outside cylinders and are connected to outside pipes leading from the steam supply pipes of the locomotive.

We claim:

1. A cylinder saddle for a locomotive made in a single casting and containing two 95 side cylinders; a centrally located cylinder; a cylindrical valve chest above each side cylinder; a cylindrical valve chest between one of the side valve chests and the central cylinder; steam inlet passages communicating 100

- directly with the several valve chests; and an exhaust passage partly surrounding the central cylinder and communicating with the several valve chests.
5. 2. A cylinder saddle for locomotives made in a single casting having flanges arranged to be secured to the side frames of the locomotive; a central cylinder and two outside cylinders, one extending on each side beyond the flanges that are secured to the frame of the locomotive; a cylindrical valve chest for each cylinder; passages forming communication between the valve chests and the cylinders; a steam inlet passage at each side of the structure communicating directly with the valve chests of the outside cylinders; a passage connecting one of said steam inlet passages with the valve chest of the central cylinder; a main exhaust passage extending under the central cylinder and partly around said cylinder and opened at a point above said cylinder; and passages connecting the several valve chests with the main exhaust passage.
10. 3. A cylinder saddle for locomotives made in a single casting and having means by which it is secured to the side frames of the locomotive; an inclined central cylinder; a side cylinder overhanging each side of the frames of the locomotive; steam chests for the side cylinders directly above said cylinders and communicating therewith; a steam chest for the central cylinder located between one of the side steam chests and the central cylinder and communicating with said cylinder; steam inlet ports directly above the side valve chests and communicating therewith; a passage connecting one of said side steam chests with the steam chest of the central cylinder; a main exhaust passage extending under the inclined central cylinder and partly around said cylinder on the opposite side to the central cylinder valve chest; and passages connecting the several steam chests with said main exhaust passage.
15. 4. A cylinder saddle for locomotives made in a single casting and having flanges arranged to be secured to the side frames of the locomotive; a curved saddle section on which the boiler is mounted, said structure having an inclined central cylinder and overhanging side cylinders; a cylindrical valve chest for each of said cylinders; passages forming a communication between the valve chests and their respective cylinders; two steam inlet passages, one at each side of the cylinder structure beyond the curved saddle and arranged to be connected to outside steam supply pipes and communicating with the valve chests of said cylinders; a passage connecting one of said valve chests with the valve chest of the central cylinder; an exhaust passage extending under the inclined central cylinder and terminating in a horizontal section above the curved saddle portion; and an exhaust passage forming communication between the several valve chests and the main exhaust passage.
